UNITED STATES PATENT OFFICE

JACOB CLARK, OF JOPLIN, MISSOURI.

ROTARY PUMP.

No. 863,022.

Specification of Letters Patent.

Patented Aug. 13, 1907.

Application filed November 14, 1905. Serial No. 287,908.

To all whom it may concern:

Be it known that I, JACOB CLARK, a citizen of the United States, residing at Joplin, in the county of Jasper and State of Missouri, have invented certain new and useful Improvements in Rotary Pumps, of which the following is a specification.

The object of my invention is a rotary pump, simple and highly effective in operation, and so constructed as to be durable, not readily susceptible to injury and 10 wear, and the parts of which are easily accessible for repair.

More particularly my invention relates to a rotary air-force and lift pump, in which air or other gaseous fluid under compression, or steam, is conducted 15 through a hollow pump shaft, and, by a novel structure of water chamber and false bottom, acts to draw the water into the pump at the base of the barrel and to force the same into a spiral water lift.

Another object of my invention is a pump structure 20 in which all the rotating parts are supported on ball bearings, and in which the ball bearings are so mounted or arranged as to be entirely above the water line of the pump, whereby they are free from injury by water, and at the same time by virtue of their location 25 and structure, as hereinafter to be described, are easy of access and repair, and permit of the ready removal of the entire pump in case of breakage.

Having set forth the object and nature of my invention I will now describe the same in detail, reference 30 being had to the accompanying drawings, in which—

Figure 1 is a view in elevation, partly cross-sectional, of the assembled pump. Fig. 2 is a view on the line 2—2 of Fig. 1. Fig. 3 is a cross-sectional view on the line 3—3 of Fig. 1. Fig. 4 is a cross-sectional view 35 on the line 4—4 of Fig. 1, and Fig. 5 is an enlarged detailed view in cross-sectional elevation of the pump bottom of Fig. 1.

Referring to Fig. 1, there is shown the hollow rotary pump shaft 1 carrying at its lower end the spiral 2, and 40 at its upper end a bevel gear 3 fixedly secured thereto, and engaging a bevel gear 4 on shaft 5 by which the pump is driven. Shaft 1 and the parts mounted thereon are all supported by means of a sleeve or collar 6 secured to the shaft by set-screw 7 through bushing 8, 45 and carrying a disk or bearing plate 9 which rests upon ball bearings 10 in ball ways 11 on a similar disk or bearing plate 12. The bearing 12 is suitably secured by bolts 13 to a fixed external support or platform 14 of any suitable nature. The entire bearing is prefer- 50 ably inclosed in a housing 14' on the support 14, and provided with suitable means of access to the bearings, as for instance oiling.

The water spiral 2 is inclosed by the water barrel 15, suitably positioned below the shaft supporting 55 bearing described. The barrel 15 is slightly spaced from the spiral 2, as indicated at 16, whereby any wear

of the spiral against the barrel is obviated. The barrel extends above the spiral in the usual way to provide for the water column to the overflow or off-take 17. It will be noted that the overflow, together with 60 the water barrel and all its contained parts lie entirely below the shaft bearing, whereby the bearings are arranged to be at all times accessible and above water level. Furthermore, the bearings although shown as positioned below the driving gear, may be situated 65 above the same, and in some instances such latter arrangement would be preferable, as rendering the bearings more open to inspection, repair and adjustment.

Referring to Fig. 5 the spiral 2 is seen to terminate at a false bottom 18 in the barrel 15. The barrel itself and 70 the hollow driving shaft 1 terminate in a diaphragm 19 forming, with the walls of the barrel and false bottom 18, a water chamber 20. The hollow shaft 1 is closed in the diaphragm 19 as by a plug 21, but communicates with the water chamber 20 by means of perforations or 75 openings 22. The diaphragm 19 is provided with perforations or water passages 23 to the water chamber 20. The false bottom 18 has a central opening 24 of larger diameter than the internal diameter of the spiral 2, but of less diameter than the external diameter of the spiral 80 so as to be overlapped by the blades of the spiral. By means of this opening the water chamber communicates with the spiral and water barrel. No particular manner of mounting the diaphragm 19 and the false bottom 18 is essential to my invention. I have, however, shown the false bottom 18 as secured to and resting upon a sleeve or ring 25, in turn secured to or integral with the diaphragm 19, which latter may be suitably secured by screws 26, or their equivalent, to the barrel. 90

The hollow shaft 1 is in communication at its upper end with a source of compressed air, or other expansible fluid, such for instance, as steam, and at the point of juncture therewith is embraced by the stuffing box or packing 27 to prevent leakage. 95

In operation, the pump shaft 1 is rotated from the shaft 5, which latter is in turn driven from a motor of any suitable type, and the shaft 1 drives the spiral mounted thereon in the direction indicated by the arrow. Simultaneously, the compressed air or other 100 fluid, entering the hollow shaft 1 at 27, passes down therethrough and passing through the openings 22 enters the water chamber 20. Thence passing upward through the opening 24 into the spiral the air draws the water through the openings 23 into the water chamber 105 and forces the same through the opening 24 into the spiral. The blades of the spiral overlapping the hole in the false bottom and rotating at considerable speed create a funnel suction effect, assisting the air in forcing the water into the spiral, and the spiral then acts in the 110 usual way to feed and lift the water column in the upper part of the barrel to the overflow or off-take 17. Upon a

- cessation of the rotation of the pump shaft, there being no valves to hold the water up it flows freely down the spiral and out of the pump, and for this reason freezing in the pump can not occur and priming is unnecessary.
5. It will be noted that no part of the working barrel or shaft is subject to the wear or friction except Babbitt boxing in which the end of the revolving hollow shaft is fitted. The only wearing part of the entire pump is that carried on the ball bearings at the platform or support above the water line and ground, and these are made of such material as involve the least possible friction.
- Although I have shown and described in detail an embodiment of my invention it is apparent that the 15 precise structure shown may be altered in many respects without involving a departure from the scope of the invention.
1. In a rotary pump, a hollow pump shaft, a spiral water lift thereon, a source of compressed air or other suitable 20 fluid in connection with the interior of said shaft, and an exit for said fluid from said shaft to feed the water to said water lift.
2. In a rotary pump, a hollow pump shaft, a water lift thereon, a source of air in connection with the interior of 25 said shaft, and an air exit from said shaft to feed the water to said water lift.
3. In a rotary pump, a hollow rotary pump shaft, a spiral water lift rigidly mounted thereon, a source of compressed air or other suitable fluid in connection with the 30 interior of said shaft, and an exit for said fluid from said shaft to feed the water to said water lift.
4. In a rotary pump, a hollow rotary pump shaft, a spiral water lift rigidly mounted thereon, a source of air in connection with the interior of said shaft, and an air 35 exit from said shaft to feed the water to said water lift.
5. In a rotary pump, a hollow pump shaft, a spiral water lift thereon, a source of compressed air or other suitable fluid in connection with the interior of said shaft, and an exit for said fluid from said shaft at the end thereof to 40 feed the water to said water lift.
6. In a rotary pump, a hollow pump shaft, a spiral water lift thereon, a source of compressed air or other suitable fluid in connection with the interior of said shaft, and a lateral exit for said fluid from said shaft to feed the water to said water lift.
7. In a rotary pump, a hollow pump shaft, a spiral water lift thereon, a source of compressed air or other suitable fluid in connection with the interior of said shaft, a pump barrel embracing said spiral, a false bottom in said 50 barrel below said spiral, a water chamber below said false bottom, a bottom to said water chamber, an exit for said fluid from said hollow shaft into said water chamber, a water inlet into said water chamber, and a passage through said false bottom from the water chamber to the spiral.
55. 8. In a rotary pump, a hollow shaft, a spiral water lift thereon, a source of air in connection with the interior of said shaft, a pump barrel embracing said spiral, a false bottom in said barrel below said spiral, a water chamber below said false bottom, a bottom to said water chamber, an exit for said fluid from said hollow shaft into said water chamber, a water inlet into said water chamber, and a passage through said false bottom from the water chamber to the spiral.
9. In a rotary pump, a hollow pump shaft, a spiral water lift thereon, a source of compressed air or other suitable fluid in connection with the interior of said shaft, a pump 65 barrel below said spiral, a water chamber below said false bottom, a bottom to said water chamber, an exit for said fluid from said hollow shaft into said water chamber, a water inlet into said water chamber through the bottom thereof, and a passage through said false bottom from the water chamber to the spiral.
10. In a rotary pump, a hollow shaft, a spiral water lift thereon, a source of compressed air or other suitable fluid in connection with the interior of said shaft, a pump 70 barrel embracing said spiral, a water chamber below said false bottom, a bottom to said water chamber, an exit for said fluid from said hollow shaft into said water chamber, a water inlet into said water chamber through the bottom thereof, and a passage through said false bottom from the water chamber to the spiral.
- barrel embracing said spiral, a false bottom in said barrel below said spiral, a water chamber below said false bottom, a bottom to said water chamber, said shaft extending through said false bottom and water chamber, a lateral exit for said fluid from said hollow shaft into said water chamber, a water inlet into said water chamber, and a passage through said false bottom from the water chamber to the spiral.
11. In a rotary pump, a hollow pump shaft, a spiral water lift thereon, a source of compressed air or other suitable fluid in connection with the interior of said shaft, a pump barrel embracing said spiral, a false bottom in said barrel below said spiral, a water chamber below said false bottom, a bottom to said water chamber, said shaft extending through said false bottom and water chamber, a lateral exit for said fluid from said hollow shaft into said water chamber, a water inlet into said water chamber through the bottom thereof, and a passage through said false bottom from the water chamber to the spiral.
12. In a rotary pump, a hollow pump shaft, a spiral water lift thereon, a source of compressed air or other suitable fluid in connection with the interior of said shaft, a pump barrel embracing said spiral, a false bottom in said barrel immediately at the base of said spiral, a water chamber below said false bottom, a bottom to said water chamber, an exit for said fluid from said hollow shaft into said water chamber, a water inlet into said water chamber, and a passage through said false bottom from the water chamber to the spiral, said passage being centrally disposed and of a diameter intermediate the inner and outer diameter of the spiral blades.
13. In a rotary pump, a hollow pump shaft, a spiral water lift thereon, a source of compressed air or other suitable fluid in connection with the interior of said shaft, a pump barrel embracing said spiral, a false bottom in said barrel immediately at the base of said spiral, a water chamber below said false bottom, a bottom to said water chamber, an exit for said fluid from said hollow shaft into said water chamber, a plurality of small water inlets into said water chamber, and a passage through said false bottom from the water chamber to the spiral, said passage being centrally disposed and of a diameter intermediate the inner and outer diameters of the spiral blades.
14. In a rotary pump, a hollow rotary pump shaft, a spiral water lift rigidly attached thereto, a source of compressed air or other suitable fluid in connection with the interior of said shaft, a pump barrel embracing said spiral, a stationary false bottom in said barrel below said spiral, a water chamber below said false bottom, a bottom to said water chamber, an exit for said fluid from said hollow shaft into said water chamber, a water inlet into said water chamber, and a passage through said false bottom from the water chamber to the spiral.
15. In a rotary pump, a hollow pump shaft, a spiral water lift thereon, a source of compressed air or other suitable fluid in connection with the interior of said shaft, a pump barrel embracing said spiral, a false bottom in said barrel below said spiral, a water chamber below said false bottom, a bottom to said water chamber, a projecting member attached to said water chamber bottom and upon which said false bottom rests, an exit for said fluid from said hollow shaft into said water chamber, a water inlet into said water chamber, and a passage through said false bottom from the water chamber to the spiral.
16. In a rotary pump, a rotary hollow pump shaft, a spiral water lift thereon, an opening in said shaft near the spiral, a stuffing box at the other end of the shaft, and a stationary fluid supply pipe in connection with the hollow shaft at the stuffing box.
17. In a rotary pump, a hollow pump shaft, a spiral water lift thereon, a source of compressed air or other suitable fluid in connection with the interior of said shaft, a pump barrel embracing said spiral, a false bottom in said barrel below said spiral, a water chamber below said false bottom, an exit for said fluid from said hollow shaft into said water chamber, a water inlet into said water chamber, and a passage through said false bottom from the water chamber to the spiral.
18. In a rotary pump, a hollow pump shaft, a spiral water lift thereon, a source of air or other suitable fluid

- in connection with the interior of said shaft, a pump barrel inclosing said spiral, a diaphragm closing said barrel immediately beneath the spiral, a centrally disposed opening in the diaphragm of a diameter intermediate the 5 internal and external diameters of the spiral blades, and an opening for said fluid in the shaft below the diaphragm.
19. In a rotary pump, a hollow pump shaft, a spiral water lift thereon, a source of air or other suitable fluid 10 in connection with the interior of said shaft, a pump barrel inclosing said spiral, a false bottom immediately beneath the spiral, an opening in the diaphragm intermediate the internal and external diameters of the spiral blades, a water chamber below said false bottom and an 15 opening for said fluid from the hollow shaft into the water chamber.
20. In a rotary pump, a hollow pump shaft, a spiral water lift thereon, a source of air or other suitable fluid in connection with the interior of said shaft, a pump 20 barrel inclosing said spiral, a diaphragm closing said barrel immediately beneath the spiral, an opening in the
- diaphragm of a diameter intermediate the internal and external diameters of the spiral blades, and an opening for said fluid in the shaft below the diaphragm. 25
21. In a rotary pump, a hollow pump shaft, means for driving said shaft, a spiral water lift at the base of said shaft, bearings for supporting said shaft and its attached parts, consisting of a bearing disk secured to said shaft, a stationary platform carrying an opposing bearing disk, and balls in grooves thereon, on which balls the shaft 30 bearing disk rests, a pump barrel spaced at a distance below said bearings, a water over-flow or off-take at the top of said barrel also well below said bearings, and a source of compressed air or other suitable fluid in connection with said hollow shaft at a point above said bearings. 35

In testimony whereof I have affixed my signature in presence of two witnesses.

JACOB CLARK.
